COMBINED SWITCH AND LIGHTNING ARRESTER

Filed Jan. 23, 1925

Witness:

Arthur Thompson

Inventor:

Henry James Lewis

UNITED STATES PATENT OFFICE.

HENRY JAMES LEWIS, OF JOHANNESBURG, TRANSVAAL, SOUTH AFRICA.

COMBINED SWITCH AND LIGHTNING ARRESTER.

Application filed January 23, 1925, Serial No. 4,314, and in Union of South Africa September 19, 1924.

This invention relates to radio or wireless outside aerials.

The object of the invention is to construct a combined switch, lightning arrester and earthing safety device for use with outside radio or wireless aerials, in such a way that when the switch is placed in position to connect the aerial with the receiving set, the lightning arrester is placed in operative position, and when the switch is placed in position to disconnect the aerial from the receiving set, the earthing safety device is placed in operative position.

The invention will be fully explained in connection with the accompanying drawing, wherein I illustrate a practical embodiment of the invention.

In the drawing Fig. 1 is a longitudinal part-sectional elevation of the combined switch, lightning arrester and earthing safety device; the dotted lines representing the wall, window frame, or portion of the building through which the device is placed, and Fig. 2 is a transverse sectional elevation of Fig. 1 on line α — α .

In the construction of the device I employ a tube 1 of appropriate dimensions which is preferably made of metal and fitted with a bush or liner 2 of suitable insulating material. This tube 1 is adapted to be placed in position in the wall, window frame, or other portion 3 of the building structure, to pass from the exterior 4 to the interior 5 thereof.

To the inner end of the tube 1 there is attached a terminal member 6 which is insulated from the tube 1 and attached metal parts by means of a piece 7. This terminal member 6 serves for connecting the aerial wire 8 leading to the set or instrument—not shown. The member 6 is constructed to allow of the insertion and withdrawal of a metallic rod 9 having a head or enlarged portion 10 fitting the bore of the member 6, which rod 9, when inserted, is adapted to engage with another and similar suitable metallic rod 11 which passes through the insulated tube 2, and forms part of a make and break device between the aerial wire 12 and, through the rods 9 and 11 and wire 8, the aerial terminal of the receiving set. The member 6 carries a terminal 13 for connecting it by wire 8 to the aerial terminal of

the set. Said member 6 is constructed with bayonet slots 14 and the head or enlargement 10 is fitted with pins 15 for making a bayonet joint between the parts 6 and 10, for detachably connecting to said member 6 the removable rod 9 of the switch device. The rod 9 is attached to a handle 16 of non-conducting material, which serves for operating the switch. The handle portion 16 with the attached rod 9 is shown connected by a cord 17 or other flexible means to a flanged cylindrical piece 18 screwed on the inner end of the tube 1 and insulated from the inner terminal member 6 by the piece 7.

The earth connection 19 from the set is shown attached to the flange of the cylindrical piece 18 by terminal screw 20, and said flange also serves for securing the device in position by means of screws 21 at the inside 5 of the wall or building 3. 22 represents a screw passing through the flanged cylindrical piece 18 and fixing the bush 2 in position in the tube 1, and also preventing unscrewing of the cylindrical piece 18 off the tube 1.

On the other and outer end of the tube 1 there is screwed or otherwise suitably fixed 80 a cylindrical piece or head 23. This piece or head is preferably made of suitable "non-arching" brass, or brass which is a good conductor but is not destroyed by arcing. To this head or piece 23 there is preferably 85 connected the earth terminal 24.

To the outer end of the piece or head 23 there is appropriately attached another terminal 25 which serves for making the connection with the wire 12 leading to the outside aerial. This terminal 25 is shown secured in an insulating bush 26 screwed into the outer end of the piece or head 23. 27 is an insulating disc placed between the outer end of the insulating bush 26 and a 95 washer 28 on terminal 25, for preventing leakage of the incoming current from the aerial terminal 25.

Inside the head 23, but insulated therefrom, there is arranged a spiral spring 29 100 which at one end bears against a washer 30 with which the screw of the terminal 25 contacts, and at the other end is in contact with a head or flange 31 provided at or near that end of the slidable rod 11 which is 105 housed and works inside the head 23. The

head or flange 31 is milled or constructed with peripheral projections, teeth or serrations, and is also made of "non-arching" metal or metal which is a good conductor but is not destroyed by arcing. The inside of the head 23, as shown, is provided with projections, teeth or serrations 32, which may be provided by forming a screw-thread through it, the screw-thread 32 serving at the ends to make the connection with the metal tube 1 at the one end and the terminal insulating bush 26 at the other. The serrated or toothed head or flange 31 is made of slightly smaller diameter than the internal diameter of the internally threaded head 23, so as to form between them a suitable arcing gap to operate as an effective lightning arrester when the set is in use.

20 Means are provided for forming an effective guide and contact for that end of the slidable rod 11 which carries the serrated flange or head 31, to preclude the possibility of accidental earth contact. Such means 25 are shown comprising the provision of an extension or continuation 33 of the slidable rod 11 beyond the flange or head 31, and the formation of a hole 34, tapered at the mouth, in the inner end of the head of the 30 screw of the aerial terminal 25. 35 is a bush or inside collar screwed inside the head 23 with which the head or flange 31 is adapted to contact when the aerial is switched off from the set.

35 When the switch is operated to connect the receiving set to the aerial the removable rod 9 is inserted and the slidable rod 11 pushed forward by it, contact is made between the slidable rod 11 and the screw of the outside aerial terminal 25, and a straight-through metallic contact is thus made between the outside and inside aerial wires 12, 8, respectively, and the lightning arrester is ready to act.

45 When the switch or removable rod 9 is withdrawn, the toothed or serrated flange or head 31 is pushed or operated by the spring 29 and makes firm and intimate contact with the bush or inside collar 35 fixed 50 in the head 23, thereby earthing the outside aerial wire 12. The electrical connection between the aerial wire 12 and earth terminal 24, when the switch or removable rod 9 is withdrawn to break the connection between the aerial and receiving set, is made through terminal 25, metal washer 30, spring 29, serrated head 31, bush or inside collar 35 and head 23. The removal of the 55 rod 9 breaks the contact between the rod 11 and the aerial wire 8 leading to the instrument or set.

What I claim as my invention and desire to protect by Letters Patent is:—

1. A device of the kind described for use 65 with outside radio or wireless aerials, com-

prising in combination a switch, a lightning arrester, and a safety earthing device, the switch including a slidable rod, a handle attached to said rod, a member to which is attached the aerial terminal for the receiving set, a bayonet joint between the slidable rod and said member, a further rod with which the slidable rod co-operates, and a part attached to said further rod which co-operates with the earth terminal to serve as the lightning arrester when the contact is made through the switch to the aerial terminal of the receiving set, as set forth. 70

2. A device of the kind described for use with outside radio or wireless aerials, comprising in combination a switch, a lightning arrester, and a safety earthing device, the switch including a slidable rod, a handle attached to said rod, a member to which is attached the aerial terminal for the receiving set, means for connecting the slidable rod to said member, a further rod with which the slidable rod co-operates, a part attached to said further rod which co-operates with the earth terminal to serve as the lightning arrester when the contact is made through the switch to the aerial terminal of the receiving set, and a spring co-operating with said part on the further rod for operating said further rod to co-operate with the earth terminal to form the earthing safety device, as set forth. 80

3. A device of the kind described for use with outside radio or wireless aerials, comprising in combination a switch, a lightning arrester, and a safety earthing device, the switch including a slidable rod, a handle attached to said rod, a member to which is attached the aerial terminal for the receiving set, means for connecting the slidable rod to said member, a further rod with which the slidable rod co-operates, a part attached to said further rod which co-operates with the earth terminal to serve as the lightning arrester when the contact is made through the switch to the aerial terminal of the receiving set, and a spring co-operating with said part on the further rod for operating said further rod to co-operate with the earth terminal to form the earthing safety device, the further rod having an extension which serves as a guide and contact and is adapted to engage with the outside aerial terminal when the switch is operated to make the contact between the outside aerial and the inside aerial terminals, as set forth. 100

4. A device of the kind described for use with outside radio or wireless aerials, comprising in combination a switch, a lightning arrester, and a safety earthing device, the switch including a slidable rod, a further rod with which said slidable rod is adapted to engage, said further rod being operatively combined with the lightning arrester and earthing safety device, a tubular casing 110

for said rod and further rod, an insulating bush in said casing, the casing at the inner end carrying the switch and a part insulated from said switch for connecting to the inside earth terminal, and a further part attached to the casing at the outer end for carrying the lightning arrester and earthing safety device and also the outside aerial and earth terminals, the casing serving for conducting the earthing current from the set to ¹⁰ the outside earth terminal, as set forth.

In testimony whereof I have signed my name to this specification.

HENRY JAMES LEWIS.
